UNITED STATES PATENT OFFICE.

JOHN W. DWIGGINS, OF FRANKTON, INDIANA, ASSIGNOR OF TWO-THIRDS
TO A. D. HURST AND WM. H. H. QUICK, OF SAME PLACE.

DESIGN FOR A FENCE-PANEL.

SPECIFICATION forming part of Design No. 22,359, dated April 18, 1893.

Application filed January 13, 1893. Serial No. 458,306. Term of patent 7 years.

To all whom it may concern:

Be it known that I, JOHN W. DWIGGINS, of Frankton, county of Madison, and State of Indiana, have invented certain new and original Design for Fences; and I do hereby declare that the following is a full, clear, and exact description thereof, reference being had to the accompanying drawing, in which like figures refer to like parts.

10 The figure is an elevation of a panel of a fence showing my design.

1 are fence posts. The posts are connected by four horizontal strands of twisted wire 3. These horizontal strands hold in place strands 15 extending upward from the lowest horizontal strand in an oblique direction to the third strand from the bottom, and then vertically from such third strand to a point above the top strand, where the strand is bent or looped, as 20 shown at 5, and extend downward to the third horizontal strand from the bottom, and from that point to the lowest horizontal strand in an oblique or diagonal direction crossing the other end of such upwardly extending strand, and

the lower ends of all upwardly extending 25 strands being straight from the lowest horizontal strand downward. Thus between the first and third horizontal strands the upwardly extending oblique strands of wire present the appearance of a lattice, and above the third 30 horizontal strand the vertical strands present the appearance of panels having rounded tops.

The chief feature of my invention consists in the horizontal strands, the upper one being crossed by vertical strands looped at the top 35 and extending vertically to the second horizontal strand from the top and the other horizontal strands crossed diagonally by strands which cross each other like lattice work.

What I claim as my invention is— 40

The design for a panel of fence, substantially as shown and described.

In witness whereof I have hereunto set my hand this 21st day of December, 1892.

JOHN W. DWIGGINS.
